CLAIM

The ornamental design for a lip oil bottle, as shown and described.

DESCRIPTION

FIG. 1 is a perspective view of the front, top, and right sides of the lip oil bottle.

FIG. 2 is a front view of the lip oil bottle.

FIG. 3 is a top view of the lip oil bottle.

FIG. 4 is a bottom view of the lip oil bottle.

FIG. 5 is a left side view of the lip oil bottle.

FIG. 6 is a right side view of the lip oil bottle; and,

FIG. 7 is a back view of the lip oil bottle.

The "g" lettering and icon forming part of the disclosure is a registered trademark of NM Beauty Industries B.V.

The broken lines shown illustrate portions of the lip oil bottle and form no part of the claimed design.

1 Claim, 7 Drawing Sheets
